UNITED STATES PATENT OFFICE

154,275

DESIGN FOR A TEXTILE FABRIC

Howard Horn, New York, N. Y.

Application April 16, 1948, Serial No. 145,761

Term of patent 3½ years

(Cl. D92—1)

To all whom it may concern:

Be it known that I, Howard Horn, a citizen of the United States of America residing in New York, county of New York and State of New York, have invented a new, original, and ornamental Design for a Textile Fabric, of which the following is a specification, reference being had to the accompanying drawing, forming part thereof.

The figure on the drawing is a face view of a textile fabric showing my new design. The dotted lines outline a design unit, which unit is repeated over a fabric as indicated by the extensions beyond the unit boundaries.

I claim:

The ornamental design for a textile fabric, substantially as shown and described.

HOWARD HORN.
